FURNITURE SIDE FRAME

William L. Gittings, Racine, Wis., assignor to
 Gold Metal Folding Furniture Co., Racine, Wis.,
 a corporation of Wisconsin

Application December 16, 1935, Serial No. 54,655

3 Claims. (Cl. 155—191)

This invention appertains to furniture, and more particularly to a novel end support for various articles of furniture, such as chairs, couches, tables, and so forth.

5 The trend in late years is toward so-called "Modernistic" furniture, which usually takes the form of highly polished metal side frames, generally constructed from tubular stock. While furniture of this character has appeal, the same 10 lacks the warmth, beauty and color of wood. It is therefore one of the primary objects of my invention to provide a furniture side-piece or frame constructed from a combination of wood and metal, whereby the new, desirable modernistic effect will be had, without the disadvantages and cost of all-metal or all-wood frames.

20 Another salient object of my invention is to provide novel means for constructing the combination side-pieces, whereby a strong and durable construction will be had, one that will be simple and easy to assemble, and one which can be placed upon the market at a reasonable cost.

A further important object of my invention is to provide a combination wood and metal 25 frame end-piece embodying a top horizontal piece and front and rear vertical pieces formed of wood, with highly polished metal corner pieces connecting the top, front, and rear pieces, the corner pieces being exposed to view so that a novel and new effect will be had.

30 With these and other objects in view, the invention consists in the novel construction, arrangement, and formation of parts, as will be hereinafter more specifically described, claimed, and illustrated in the accompanying drawing, in which drawing:

Figure 1 is a side elevation showing one of my improved side frames applied to a chair.

Figure 2 is an enlarged fragmentary detail 40 section of one corner of the side frame, with parts thereof broken away and in section.

Figure 3 is a detail transverse section taken on the line 3—3 of Figure 2, looking in the direction of the arrows.

45 Figure 4 is a detail, fragmentary, and perspective view, showing one corner of the novel side frame.

Referring to the drawing in detail, wherein 50 similar reference characters designate corresponding parts throughout the several views, the letter S generally indicates one of my improved side frames applied to a chair C. While in the drawing I have shown the side piece applied to a chair only, it is to be understood that the same can be utilized in various other types of

furniture, such as couches, tables, foot-stools, or the like.

The novel furniture side frame S comprises vertical, front and rear pieces 5 and 6, and a top horizontal piece 7. These pieces 5, 6, and 7 are all formed from wood, and if preferred the top piece 7 can be painted a contrasting color from the front and rear pieces 5 and 6.

In accordance with my invention the wood pieces 5, 6, and 7 are connected together by 10 metal corner pieces 8 and 9. These corner pieces 8 and 9 can be constructed from flat metal stock, and are highly polished or chromium plated. Each of the corner metal pieces 8 and 9 includes an arcuate body portion 10, and 15 right angularly disposed attaching portions 11 and 12. The attaching portions 11 and 12 are reduced in width so that stop shoulders 13 will be formed at the ends of the arcuate body portion 10. In forming the side frame the inner faces of the wood pieces to be joined are 20 grooved to receive the attaching portions 11 and 12, and thus the attaching portions are countersunk within the inner faces of the wood pieces, and lie flush with said inner faces. Screws or 25 other fastening elements 14 are employed for rigidly securing the attaching portions in place, and it is to be noted that the shoulders 13 on the arcuate body portion fit up against the adjacent ends of the wood pieces, and constitute 30 thrust or bearing surfaces.

The adjacent ends of the wood pieces are preferably rounded off, as at 15, so that abrupt corners are eliminated, which reduces the liability of the garments of persons catching thereon, and adds to the beauty and artistic effect of 35 the furniture. The highly polished metal corner pieces being exposed to view blend with the wood pieces, and give a highly desirable new and ornamental effect.

In the present showing the front and rear pieces 5 and 6 are rigidly secured to a side base piece 16 of wood, but it is to be understood that the ends of the front and rear pieces 5 and 6 can be provided with feet in lieu of the 40 base, or the base can be constructed similarly to the top piece 7, and connected with the front and rear pieces 5 and 6 by the ornamental corner metal pieces.

In Figure 1 a chair bottom 17 and a back 18 are rigidly secured to the side frames, and the wood pieces permit the expeditious connecting of the chair back and bottom thereto. By my improved construction, not only is a novel and 45 modernistic effect obtained, but a strong and 50 55

durable construction is had, which will be simple and inexpensive to manufacture.

By providing the corner metal pieces, the bending of the wood is eliminated, and consequently the likelihood of the wood breaking and splintering at the bend is prevented.

Another important feature of the invention is that the corner metal pieces being detachably connected to the wood pieces permit the furniture side frames to be shipped in a knock-down condition, which saves space, and so forth. This is impossible with all-metal side frames, which have to be preformed at the factory. The fact that the inner faces of the wood pieces are grooved to receive the attaching portions of the metal corners facilitates assembling, and insures correct location of the parts.

Changes in details may be made without departing from the spirit or the scope of my invention, but what I claim as new is:

1. In an article of furniture, a pair of angularly disposed wood pieces having their adjacent ends spaced, an ornamental metal corner

piece connecting said adjacent ends including a body portion located between said ends and exposed to view, and attaching portions countersunk in the inner faces of said wood pieces, said attaching portions being of less width than the body portion whereby to define shoulders abutting the ends of said wood pieces.

2. In an article of furniture, a side frame including a pair of wood strips angularly disposed relative to one another having their adjacent ends spaced, an ornamental metal piece formed from flat stock connecting said adjacent ends, said metal piece including an arcuate connecting body portion located between said spaced ends and exposed to view, and angularly disposed attaching portions, the attaching portions being countersunk in and secured to the inner faces of the wood pieces, said attaching portions being of less width than the arcuate body portion whereby to define shoulders abutting against the ends of said wood pieces.

WILLIAM L. GITTINGS.
